PROCESS AND MACHINE FOR PRINTING
UPON THE OPEN EDGES OF BOOKS

Fred Meyer, Chicago, Ill.

Application July 12, 1946, Serial No. 683,184

22 Claims. (Cl. 101—41)

1

This invention relates to printing and more particularly to a process and machine for printing upon the opening edges of the leaves of books, such as directories, textbooks, magazines, catalogs or the like on which it is desirable to provide an index for the purpose of readily locating the various topics or classes of subject matter therein. The invention also has application to the printing of advertising or decorative matter on such opening edges.

Heretofore, in view of the desirability of such an inexpensive type of indexing, advertising, or ornamentation, various processes and machines have been devised for printing upon the opening edges of the leaves of books, but for one reason or another such processes or machines were found to possess inherent disadvantages or were ineffective in operation, thereby creating problems which have remained unsolved until the present invention and which have retarded the commercial use of such edge printing. Because the opening edges of the leaves are unevenly supported when a book is clamped or held in normal position thus preventing the type members from engaging the edges with equalized pressure and resulting in uneven impressions and printing which became faint when the book was flexed, the process and apparatus disclosed in my earlier Patent No. 1,249,448 of December 11, 1917, were devised in an attempt to accomplish more even and clear cut printing.

In practicing the process of my earlier patent, a flexible book was bent intermediate its opening edges and its back edges so that the opening edges of the leaves were arranged en echelon in a plane forming an angle of less than forty-five degrees to the planes of the leaves. The type was then caused to bear against the edges and exposed edge surfaces of the leaves in a direction substantially at right angles to the plane of the book edges, the book leaves having been clamped together by a member bearing downwardly against the upper sheet adjacent its opening edge. As a result of printing according to my earlier process and apparatus, an index or other printing was provided which was visible not only when the edges of the leaves were in normal vertical alignment but also when the book was flexed or bent in either direction so that the edges of the leaves were drawn out of position to form an inclined plane.

Although the results obtained by the practice of the process and use of the apparatus disclosed in my said earlier patent were considerably better than any obtained by earlier meth-

2

ods and structures at that time, it was found upon its further use that certain conditions arose which caused undesirable variations in the results obtained. One such variation was occasioned by differences in the thickness of the paper, causing some books to be thicker or thinner than the initial book in accordance with which the printing form had previously been set up, and because no means had been provided to compensate for variations in paper thickness, the printed matter on the thicker or thinner books was out of registry beyond commercial acceptance.

It was further discovered that because of the manner in which the pages were clamped during the printing operation, the opening edge portions of the leaves were somewhat unconfined and almost wholly uncompressed, and thus were capable of some relative yielding movement as they were engaged by the indexing type. This yielding movement of the leaves caused a printing impression on their edges that was somewhat smudged and less sharp than commercially acceptable. No means was provided to cause the edges of the leaves to present a substantially nonyielding rigid printing face. Further, no means was provided to arrest and prevent movement of the entire book at the time of printing, i. e., from the time the inked type first touched the opening edges to the time of finally leaving said opening edges.

Also, in my earlier process there was some degree of offsetting of the ink from the upper edge surface of one leaf to the under edge surface of the leaf immediately thereabove so that when the book was flexed in either direction out of normal position, the printing would be visible. However, this offsetting of my early process was uncontrolled in that it resulted naturally from the limited movement of the leaves during handling of the books, and when the book in use was flexed in the direction opposite to that in which it had been flexed for printing, the visible printing resulting from the uncontrolled offsetting was indistinct and smudged and therefore incapable of meeting the commercial requirements of sharp printing impressions when flexed in either direction.

It is, therefore, one of the objects of my invention to provide an improved process and apparatus for printing sharp and clear impressions upon the opening edges of the leaves of books such as directories, textbooks, magazines, catalogs or the like.

Another object of the present invention is to

provide an improved process and machine for printing upon the opening edges of the leaves of books in accordance with which clear and sharp printing impressions are made and are then offset by a controlled series of operations so that the printing is distinctly visible not only when a book is in normal position but also when it is flexed in either direction.

Still another object is to provide an improved process and apparatus for printing upon the opening edges of the leaves of books in accordance with which a book is flexed intermediate its edges so that the opening edges thereof are en echelon in a plane forming an angle to the planes of the leaves and the upper surface edge portions are slightly exposed, the type is then caused to print on the edges and on said slightly exposed edge portions of the upper surfaces of the leaves, the book is then restored to normal position with the opening edges thereof in a plane perpendicular to the plane of the leaves, pressure is then applied at right angles to the leaves to compress them at their opening edges and to effect a definite offsetting of the ink from the upper surface edge portion of one sheet to the under surface edge portion of a sheet immediately thereabove, and then the book is again flexed intermediate its back and front edges with the opening edges thereof under compression to effect a further offsetting of the ink by a wiping or rubbing action.

Another object is to provide an improved process and apparatus similar to that referred to in the next preceding object except that as a final operation the book may be flexed back and forth under pressure in a weaving or rippling motion to effect a definite and extended offsetting by a wiping action in both directions.

A further object of the invention is to provide an improved process and apparatus for printing upon the opening edges of the leaves of books in accordance with which the inclined surface formed by the opening edges of the book when flexed is provided with sufficient rigidity as to be substantially unyielding when the type members are forced thereagainst during the printing operation, thereby effecting sharp, clear printing impressions.

Another further object of the invention is to provide an improved process and apparatus for printing upon the opening edges of the leaves of books in accordance with which pressure is applied against the inclined surface formed by the opening edges of the book when flexed so that said inclined surface to be printed will be substantially rigid and unyielding when the type members are forced thereagainst during the printing operation, thereby effecting sharp, clear printing impressions.

A still further object of the invention is to provide an improved process and apparatus for printing upon the opening edges of the leaves of books in accordance with which a book is flexed or bent intermediate its edges so that the opening edges thereof are en echelon in a plane forming an acute angle to the planes of the leaves and the upper surface edge portions are slightly exposed, the movement of the book being arrested and the book being supported on its underside by a platen and being clamped thereagainst by a member engaging the upper leaf adjacent its opening edge portion, then a pressure member is brought to bear against the inclined surface formed by the opening edges so as to compress the opening edge portions and to cause the said

inclined surface to be substantially rigid and unyielding when the type members are forced thereagainst during the printing operation, thereby effecting sharp, clear printing impressions.

Another further object of the invention is to provide an improved process and apparatus similar to that referred to in the next preceding object except that the said pressure member and the movable bed carrying the type members are moved on the same arc against said inclined surface to be printed and the pressure member may be provided with apertures through which the type members are projected for printing.

Another object of the present invention is to provide an improved process and apparatus for printing upon the opening edges of the leaves of books in accordance with which the variation in the thickness of the paper leaves is compensated for and the printed impressions from book to book are always caused to be in proper registry with pages being printed.

Still another object is to provide an improved process and apparatus for printing upon the opening edges of the leaves of books in accordance with which a book may be flexed intermediate its back bound and front opening edges in such a manner that the opening edges thereof are en echelon in a plane forming an angle to the planes of the leaves and that the distance between the opening edges of the top and bottom leaves is fixed or constant regardless of variations in the thickness of the paper stock comprising the leaves being printed, the exposed edges of the top and bottom leaves of respective books always reaching the same two extreme spaced positions and therefore the spread of the exposed edges always being constant from book to book, and, correspondingly, the exposed opening edges of the intermediate pages assuming substantially their proper spaced relationship.

Another object is to provide an improved machine for printing upon the opening edges of the leaves of books that is automatic and capable of carrying on the various steps of my improved process simultaneously with respect to a plurality of books and with a minimum of handling and attention by an operator.

Other and further objects and advantages of the invention will become apparent as this description progresses, reference being had to the accompanying drawings in which:

Figure 1 is a side elevational view of an old and well-known type of printing press to which a mechanism embodying the present invention has been applied and by which the various steps of the process comprising the present invention may be carried out, the press being shown in open position.

Fig. 2 is a side elevational view of the press shown in Fig. 1 but illustrating the press in closed, printing position.

Fig. 3 is a rear elevational view of the press in closed or printing position, taken on the line 3-3 in Fig. 2 looking in the direction of the arrows.

Fig. 4 is an elevational view of the movable bed and inking and printing mechanism taken on the line 4-4 in Fig. 2 and looking in the direction of the arrows, but with lower portion of the inclined platen bed removed and certain elements broken away for clarity.

Fig. 5 is an elevational view of the press taken on the line 5-5 in Fig. 1 and looking in the direction of the arrows, showing the inclined platen bed or chute with the four operational

positions of the four books which may be passing through the press simultaneously.

Fig. 6 is a combined vertical sectional view of the press taken on the line 6—6 in Figs. 3 and 4, respectively, looking in the direction of the arrows and with certain parts eliminated for clarity, and showing the four relative positions of four books in the successive operational stages when the press is in closed printing position.

Fig. 7 is a detailed top plan view of the rocker chute and pressure bar and chains of position B of the machine.

Fig. 8 is a front elevational view of the structure illustrated in Fig. 7.

Fig. 9 is a side elevational view of the same.

Fig. 10 is a vertical longitudinal sectional view taken on the line 10—10 in Fig. 8, looking in the direction of the arrows.

Fig. 11 is a detailed vertical sectional view of the cam bar and roller carrier structure for controlling movement of the floating clamp bar of position B with certain of the parts broken away, taken on the line 11—11 in Fig. 3 looking in the direction of the arrows.

Fig. 12 is a detailed vertical sectional view of the cam bars and roller carrier structure for controlling movement of the rocker chute locking arm of position B, for controlling movement of the pin carrier locking arm of position B, and for controlling movement of the stop locking arm of position D with certain of the parts broken away, taken on the line 12—12 in Fig. 3 looking in the direction of the arrows.

Fig. 13 is a detailed vertical sectional view of the cam bar and roller carrier structure for controlling movement of the stop locking arm of position C, with certain of the parts broken away, taken on the line 13—13 in Fig. 3 looking in the direction of the arrows.

Fig. 14 is a detailed side elevational view showing the relative positions of certain of the parts of position B in broken away condition and in open non-printing position.

Fig. 15 is a view similar to that of Fig. 14 but with the parts illustrated in printing position.

Fig. 16 is an enlarged vertical sectional view showing the opening edges, the compressible mat and the type members in printing position.

The printing machine to which the mechanism embodying the present invention has been applied and by which the various steps of the process comprising the present invention may be carried out is illustrated in the drawings as comprising right and left side frames 20 and 21 which are maintained in spaced supporting relation by cross braces 22, 23, 26 and 26a extending therebetween adjacent their upper and lower ends and by the various cross shafts of the machine to which reference will be made in detail hereinafter. The side frames 20 and 21 are of practically identical construction and their upper edges are parallel and inclined downwardly from the rear to the front of the machine, thereby providing spaced supports for an inclined platen bed or chute over and down which successive books may pass by gravity during the successive operational stages. The frames 20 and 21 each have aligned circular openings 24 and 25, respectively, providing bearing surfaces for a power shaft 27 extending transversely of the machine and projecting beyond the frames 20 and 21. On the left end of the power shaft 21, as viewed from the rear in Fig. 3, there is keyed a flywheel 28, while on the other or right end thereof there is keyed a pulley 29 which is adapted to be operably connected by means of a

belt or otherwise to a source of power (not shown).

A pinion gear 30 is keyed to the power shaft 27 intermediate the pulley 29 and the right side frame 20 and is in constant mesh with a large driving gear 31 which is keyed to the right end of a main drive shaft 32. The drive shaft 32 also extends transversely of the machine and also projects beyond the side frames 20 and 21. A drive wheel 33 corresponding to the driving gear 31 is also keyed on the left end of the drive shaft 32, and rocking movement of the movable bed 34 to and from printing position is effected upon rotation of the driving gear 31 and the drive wheel 33 by means of connecting rods 35 and 37, respectively. The rearward ends of the connecting rods 35 and 37 are eccentrically and pivotally connected to the driving gear 31 and the drive wheel 33, respectively, while their forward ends are pivotally connected to the outer projecting ends, respectively, of a fixed shaft 38 which extends transversely of and is carried by the bed 34. The movable bed 34 is pivoted on its lower left and right legs on a shaft 39 which is mounted between and projects beyond the left and right side frames 20 and 21 at the lower forward portions thereof. Thus upon rotation of the shaft 27 the rocker bed 34 is caused to move from open position to closed printing position by means of pinion 30, driving gear 31 and drive wheel 33, and connecting rods 35 and 37.

As is also conventional in printing presses of this general type and as shown in Figs. 1, 2 and 4 of the drawings, a pair of inking rollers 40 and 41 rotatably mounted in double saddles 42 and 43 are operably mounted on the bed 34 and are adapted to roll over an inking disc 44 at the top of which may be secured in the usual manner a fountain bed and roll (not shown) containing the ink supply. The disc 44 may be centrally pivoted for rotative movement on an upstanding bracket 46 mounted on the upper portion of the bed 34. The saddles 42 and 43 are pivoted on studs 45 and 47, respectively, carried on the upper ends of rods 48 and 49 which are retained in roller frames 50 and 51 on each side of the bed 34 by compression springs 52 and 53, respectively. The roller frames 50 and 51 are joined by a connecting plate 53a and are pivoted on the respective end portions of the cross shaft 38 intermediate the forward ends of the connecting rods 35 and 37 and the bed 34, and the movement of these roller frames 50 and 51 is effected upon movement of the bed 34 by means of a rocker arm 54 pivotally connected to the left roller frame 51 and a fixed stud 55 projecting from the left side frame 21. Thus as the bed 34 is caused to rock from its closed printing position shown in Fig. 2 to its open position shown in Fig. 1, the roller frames 50 and 51 will be rocked downwardly in a counterclockwise direction causing the inking rollers 40 and 41, which have become coated with ink from the disc 44 in the usual manner, to move downwardly and over and in contact with the type members 57 carried by the bed 34. Conversely, as the bed 34 is rocked from its open to closed printing position, the rollers will be returned over the type members to their Fig. 2 position before the bed is closed.

The type members 57, which may also comprise any plate, cut or printing instrument of any kind, may be mounted with furniture or other filler 58 in the conventional manner, in a chase 59, and the chase 59 may be secured to

the bed 34 by means of a clamp 60 for movement therewith.

The foregoing parts which have been described generally comprise a mechanism that is conventional to old and well-known printing machines of this type, and hereinafter there will be described in detail the novel modifications and additions in structure which have been made thereto in order to carry out the steps of the improved and novel process.

As shown more clearly in Figs. 5 and 6, the improved machine is capable of handling four books at the same time, the four positions or books being designated on the inclined platen bed or chute by the letters A, B, C and D. It is to be understood that the term "book" or "books" wherever used herein may include any possible combination of flexible sheets whose opening edges are to be printed. The term may include any book, magazine, directory or catalog, either singly or in multiple, or the flexible portion of an inflexible book before being bound in a rigid cover, or may mean any combination of sheets which may be flexed for the purpose of printing on their opening edges. A book may be placed initially in a chute comprising position A and thereafter the book may automatically pass downwardly by gravity to the successive positions B, C and D, in which positions it is processed in accordance with the steps of my improved process. As soon as a book passes downwardly from position A to position B, the operator may place another book to be printed in position A, although automatic feed means (not shown) of suitable structure and operation may be provided. Likewise, when a book leaves the machine from position D, it may automatically be removed by means of a conveyor (not shown). Position A is merely a feeding position while in the successive positions B, C and D the books are being operated on or processed simultaneously but in which positions different successive steps are being performed, as will be more fully described hereinafter.

The stationary inclined platen bed or chute down which the books slide to their successive positions comprises a plurality of flat boards or plates 61, 62, 63 and 64 mounted on and extending between the inclined top edges of the right and left side frames 20 and 21. As shown more particularly in Fig. 6, the boards 62, 63 and 64 are spaced apart but a slight distance but the space between the boards 61 and 62 is substantial. This latter space, however, is bridged by the bottom wall of a rocker chute 65 in its normal position so that together the board 61, the rocker chute 65 and the boards 62, 63 and 64 provide an inclined platen bed or chute. In order to facilitate the downward passage of the books from position to position, a plurality of sheets of timpin paper (not shown) arranged in shingle fashion may be used.

Position A

Referring now more specifically to the mechanism which is operable in and comprises position A of the improved machine and shown more particularly in Figs. 5 and 6 of the drawings, there is secured to the upper inclined surface of the board 61 an adjustable chute comprising upstanding adjustable side guide plates 66 and 67, composed of sheet metal and having horizontal transversely slotted flanges 68 and 69 which are engaged by thumb bolts 70 and 71, respectively. The guides 66 and 67 by the foregoing construction may, therefore, be readily adjusted trans-

versely of the machine to accommodate books of different heights. A book with its opening edges directed forwardly and downwardly may be placed at the top of the machine by the operator with its bottom leaf in contact with the board 61 and it may thereafter slide downwardly by gravity between the guide plates 66 and 67 until its front opening edges are engaged by an automatic stop 72 which is pivoted on an upstanding stud 73 mounted in the board 61. The stop 72 is provided with a counterbalance portion 74 which normally urges the stop 72 in a counterclockwise direction about the pivot 73 into book-engaging position, this counterclockwise movement being limited by an upstanding lug 75 carried by the board 61 and adapted to engage the counterbalance portion 74. The weight of a book is greater than the counterbalance portion 74 and therefore to prevent the stop 72 from pivoting in a clockwise direction to permit passage of the book downwardly there is provided an upstanding locking stud 77, which, as shown in Fig. 6, is pivotally connected on the upper end of an arm 78 below the board 61 and extends upwardly through a supporting guide bracket 76a, the cross brace 23 and the bed 61 beyond which it projects into the path of movement of the counterbalance 74.

During the cycle of machine operation when the book in position A is to be released to slide downwardly to position B, the locking stud 77 is retracted downwardly below the counterbalance portion 74 to permit the stop 72 to be forced in a clockwise direction out of the path of the book. Retraction of the stud 77 is accomplished automatically upon machine operation by means of the following structure. As shown more particularly in Fig. 6 of the drawings, the lower end of the arm 78 is pivotally connected to the upper end of a cam bar 79 which is provided with a peaked cam portion 80 and pivoted on a cross shaft 81 extending between and beyond the left and right side frames 21 and 20. The cam portion 80 of the cam bar 79 is urged into engagement with a roller carrier sleeve 76 secured on the drive shaft 32 for rotation therewith and the locking stud 77 is urged into fully projected position above the board 61, by means of a spring 82 which is tensioned between the upper end of the cam bar 79 and the cross brace 23. Retraction of the stud 77 is accomplished by means of a roller 83 extending between two spaced annular collars forming a roller carrier 84 and secured to the carrier sleeve 76 for rotative movement therewith. The roller 83 is so positioned on the carrier 84 that it will, when it is desired to permit the book in position A to advance, engage the cam portion 80 and rock the cam bar 79 rearwardly, thus effecting retraction of the stud 77 by downward movement of the arm 78.

After the book has passed downwardly by gravity on the inclined platen bed to position B and the roller 83 has passed beyond the cam portion 80 of the cam bar 79, the stop 72 under the urge of the counterbalance portion 74 restores itself to normal book-engaging position and the stud 77 is again projected up through the board 61 to stop locking position. When the stop 72 has been fully restored and locked the operator may then insert another book in feeding position A on the machine. Although not shown in the drawings, it is apparent that suitable mechanism may be devised for automatically delivering books to position A.

Position B.

When the book from position A slides downwardly toward position B, it passes between transversely adjustable guide plates 85 and 87 which are similar in general structure and operation to guide plates 66 and 67 of position A and which are mounted on the rocker chute 65 for movement therewith. Downward movement of the book is continued until its lower opening edges engage a pair of upstanding retractable pins 88 and 89 which are mounted on a transverse carrier 86 below the platen board 62 and serve to correctly position the book in position B. It is in stage or position B that the type members 57 on the movable bed 34 are caused to bear against and print on the opening edges of the leaves of the book, although in this position the book must first be properly clamped, flexed and compressed against movement in preparation for engagement with the type members.

As shown in Figs. 5 and 6 and in detail in Figs. 7 to 10 inclusive, of the drawings, the rocker chute 65 comprises a flat bottom wall 90, forming part of the inclined platen bed when in normal non-printing position, and longitudinally extending and upstanding side walls 91 and 92 on each side of the bottom wall 90. The side walls 91 and 92 are secured to the inner faces of U-shaped bearing members 93 and 94 which are fixedly mounted on a cross rock shaft 95 for rock movement therewith, the cross rock shaft 95 being journaled in the side frames 20 and 21. The bottom wall 90 extends only rearwardly from the rock-shaft 95 and platen board 62 extends forwardly therefrom under the forward portions of the rocker chute side walls 91 and 92.

In order to securely hold and clamp a book as it is flexed upon rearward and downward rocking movement of the rocker chute 65 so that the back edges thereof are maintained in their normal relative positions, there is provided an adjustable cross bar 97 (Figs. 7 to 10, inclusive) supported at its respective ends by bolts 98 which are threadedly received within spaced threaded openings in the U-shaped bearing members 93 and 94 on each side of the rocker chute 65. Beneath the cross bar 97 there is a floating clamp bar 99 supported at its respective ends on bolts 100 which extend downwardly from the respective ends of the cross bar 97 within the central openings of the bearing members 93 and 94. The respective ends of the floating clamp bar 99 project through and beyond the bearing members 93 and 94, and the bar is freely mounted on the bolts 100 for vertical movement relative thereto, the vertical movement being controlled by a plurality of spaced compression springs 101 extending vertically between and spacing the cross bar 97 and the floating bar 99. As shown more particularly in Figs. 7 and 10 of the drawings, a rearwardly and upwardly extending guide plate 102 is secured to the underside of the floating clamp bar and serves to direct the opening edges of the book leaves under the clamp bar 99 where the top leaf thereof is engaged by a plurality of spaced pointed set screws 103. These set screws are carried by the clamp bar 99 and extend downwardly therethrough and serve to prevent slippage of the book when clamped.

To facilitate the free passage of a book under the guide plate 102 when the rocker chute bottom wall 90 is parallel with the stationary platen 62, provision is made for raising the floating clamp bar 99, and to this end, as shown in Figs. 5, 14, 75,

and 15 of the drawings, there are a pair of lifting arms 104 having inwardly directed studs 104a at their forward ends adapted to engage the under surfaces of the projecting ends of the floating clamp bar 99. These lifting arms 104 are pivoted intermediate their ends on pins 105 projecting inwardly from the side frames 20 and 21, and their bifurcated rear ends are pivotally connected to spaced rods 108 extending upwardly from a saddle 109 (Figs. 3, 14 and 15), which saddle has downwardly and rearwardly extending forked arms 110 pivoted to the upper ends of cam bars 111 and 112 also pivoted on the cross shaft 81. The cam bars 111 and 112 are held against sleeve 76 by springs 116 and are adapted to be engaged with and rocked rearwardly by rollers 113 rotatably supported in roller carriers 115 and 117 also mounted on the carrier sleeve 76 on the drive shaft 32. Thus, when the machine cycle requires passage of a book to position B, the cam bars 111 and 112 engage with the rollers 113 upon rotation of the carrier sleeve 76, and the rearward ends of the lifting arms 104 are pulled downwardly by the rods 108, thereby raising the forward ends of the arms 104 and consequently the floating clamp bar 99. When a book has slid downwardly to its extreme position against the stop pins 88 and 89 in position B, the floating clamp bar 99 is released from its raised position by the passing of the rollers 113 beyond the cam bars 111 and 112, and thereafter the book becomes clamped in the rocker chute 65 by the force of the compression springs 101, the floating clamp bar 99 engaging the book intermediate its front and rear edges.

After the book is clamped as above described, rocking movement of the rocker chute 65 is effected upon movement of the movable bed 34 toward printing position by means of the following arrangement of parts. Sprockets 118 are keyed on the respective ends of the rock shaft 95 which projects beyond the side frames 20 and 21, and mesh with chains 119 whose ends extend downwardly and forwardly therefrom on either side of the machine. The chains 119 are tensioned over the sprockets 118 by means of springs 120 and 121, the upper springs 120 being lighter and connecting the upper ends of the chains 119 to the respective legs of the movable bed 34 and the lower springs 121 being heavier and connecting the lower ends of the chains 119 to the forward ends of bracket arms 122. The bracket arms 122 are each pivoted on the ends of the shaft 81 which project beyond the side frames 20 and 21 and each is provided with a pin 123 on top of which the reduced rearward end portions of thrust arms 124 are freely slidable until engaged by the shoulders 125 thereof. The forward ends of the thrust arms 124 are pivoted to rearwardly directed brackets 127 carried on the vertical legs of the movable bed 34.

By the foregoing mechanism, as the bed 34 is moved rearwardly to printing position, the arms 124 are thrust rearwardly, the bracket arms 122 being caused to pivot in a clockwise direction, as viewed in Figs. 1 and 2, upon engagement of the shoulder 125 with the bracket pins 123. Clockwise movement of the arms 122 pulls downwardly on the heavy springs 121 and chains 119 and extends the light springs 120, so as to rotate the sprockets 118 and the rock shaft 95 in a counter-clockwise direction, thereby causing the rocker chute 65 with a book clamped therein, as above described, to be rocked rearwardly and downwardly, as shown in Figs. 2 and 6 of the drawings. When the rocker chute 65 reaches its rotational

limit, the heavy springs 121 then become extended by continued movement of the bracket arms 122. In this position the book will be bent or flexed around the rocker shaft 95 preparatory for printing with the forward portions of the book adjacent the opening edges supported on the platen board 62. When the bed 34 is moved in a reverse direction after the printing operation, the springs 120 serve to pull the rocker chute 65 back into its normal position, since the force of the heavier springs is released by such bed movement.

In order to retain the rocker chute 65 in a fixed book-flexing position so as to correctly position the opening edge of the lower leaf from book to book, there is provided a downwardly extending locking arm 128 pivoted on a bracket 129 secured on the underside of the cross brace 23 and having its upper curved end pivotally connected to a link 130 which in turn is pivoted to a cam bar 131 (Figs. 1, 2, 12, 14 and 15). The cam bar 131 is pivoted to a bracket 132 secured on the under side of the top cross brace 22 and extends downwardly and terminate in a curved end which engages the sleeve 76. The lower end of the locking arm 128 is notched for engagement with the side and upper surface of the rocker chute cross bar 97 prior to, during, and immediately following the printing operation. The cam bar 131 is adapted to be engaged by a roller 133 in a roller carrier 134 and held in the rearward position shown in Figs. 2 and 12, rearward movement of the cam bar 131 causing the notched end of the locking bar 128 to be rocked forwardly into engagement with the rocker chute cross bar 97 after the rocker chute 65 has been rocked rearwardly. The locking arm 128, therefore, serves to lock the rocker chute 65 in fixed position which is definite and constant from book to book and fixes the resting point of the opening edge of the bottom sheet of the book on the platen board 62. A spring 135 tensioned between the cam bar 131 and the locking arm 128 serves to return the said bar and arm to their inoperative position after the roller 133 passes out of engagement with the cam bar 131 upon completion of the printing operation.

In order to clamp the book in its flexed position down against the rocker shaft 95 to facilitate the printing operation, there are provided a plurality of flexible clamping members comprising chains 137 having their upper ends secured in spaced relation to the forward face of the floating clamp bar 99 and having their other ends secured in spaced relation to a tapered transverse pressure bar 138 to which is fastened a pressure plate 139. The pressure bar 138, which is adapted to engage and be pressed downwardly against the top leaf of the book adjacent its opening edge, is supported above the platen board 62 by vertical side arms 140 (Figs. 1, 2 and 5), and the arms 140 extend downwardly on either side of the machine through guide brackets 141 projecting from the side frames 20 and 21. The ends of the arms 140 and the brackets 141 are provided with horizontally directed pins 142 and 143, respectively, between which are connected springs 144, forming a resilient means for supporting the pressure bar 138 and normally urging it to raised position. In order to return the pressure bar 138 to its normal spaced position shown in Fig. 1, there are provided a pair of springs 146 having their lower forward ends secured to the platen board 63 and their respective upper rearward ends connected to the lower ends of wires 146a 75

fastened in spaced relation to the pressure bar 138.

The pressure to be transmitted downwardly against the flexed book in position B by the chains 137 and the pressure bar 138 is provided by means of pressure cam bars 145 and 145c on each side of the machine pivoted at 147 toward their rearward ends to rearwardly directed ears 148 on the side frames 20 and 21. As shown in Fig. 6, the cam bar 145c is curved to provide clearance for the fixed stud 55 on the left side frame 21. The cam bars 145 and 145c have upper cam surfaces 149 at their forward ends and a plurality of shims 150 bolted to the under surfaces of those ends to provide adjustable bearing members adapted to engage the top surface of the pressure bar 138. Adjustment for the processing of different publications may be effected by varying the thickness of the shims 150 in the bearing members. The cam bars 145 and 145c are normally urged to raised position against limiting stops 145b by springs 145a tensioned between the rearward ends of the cam bars 145 and 145c and the side frames 20 and 21. The pressure engagement of the pressure cam bars 145 downwardly against the top of the tapered pressure bar 138 is effected by means of rollers 151 mounted on the movable bed 34 near its upper rearward portions and which will engage the forward portions of cam surfaces 149 of the cam bars 145 and 145c, as the bed 34 approaches its printing position, and forces the pressure bar 138 downwardly against the top leaf of the book adjacent its opening edge. This action, operating through pressure chains 137, pulls rocker chute 65 in a clockwise direction against the tension of heavy springs 121 until the shoulder of the locking arm 128 stops this clockwise movement of the cross bar 97 and the rocker chute 65. The rearward portions of the cam surfaces 149 are of such an arc that full and constant pressure is applied to the pressure bar 138, and consequently to the pressure chains 137 and to the book, immediately preceding, during and immediately following the actual printing impression.

After the rocker chute 65 has been locked in its proper rearward position by the locking arm 128, continued downward movement of the pressure bar 138 actuated by engagement of cam bars 145 and 145c with the rollers 151 causes the pressure chains 137 to be pulled under relatively great pressure around and downwardly against the curving upper surface of the flexed book, the chain pressure and that of the pressure bar 138 therefore being substantially radially inwardly against the rock shaft 95 and downwardly against the platen board 62. By the foregoing construction embodying the fixation of the position of the pressure cams 145 and 145c by the pressure rollers 151, the resting point or the point to which the opening edge of the top sheet is forced is constant or fixed from book to book regardless of reasonable variations in the thickness of the paper of which successive books may be composed. Since the degree of pressure applied to respective books is dependent upon the thickness of the paper, the pressure will be less where the paper is thinner, the pressure rollers 151 being in operably fixed positions and the cam bars 145 and 145c incapable of being pressed downwardly thereby the additional extent permitted by the thinner paper. Under such conditions the opening edge of the top leaf of the book will always arrive at the desired and same fixed point as that of the initial book to which

the type has been set up in proper registry. Conversely, if the thicknesses of the paper leaves comprising a book should be thicker than the initial one, then the pressure exerted against the book by the cam bars 145 will be greater but the opening edge of the top leaf upon full compression will attain the same fixed point as the opening edges of the initial or thinner leaved books. Thus, the opening edges of the upper and lower sheets of respective books are always forced to the same fixed positions and the spread of the opening edges of respective books, or, in other words, the distance between the opening edges of the top and bottom leaves of respective books when in printing position, will be the same from book to book and no consequent adjustment is required after the mechanism has been set up to handle paper leaves of a certain range of thickness. As a result, the index which will be printed on the opening edges of the books will be in proper registry even though the paper of the leaves of books may vary somewhat.

Although the floating clamp bar 99, the chains 137 and the pressure bar 138 compress the book inwardly against the rock shaft 95 and the platen board 62 in position B, the opening edges of the leaves of the book upon which the printing impressions are to be made are still almost wholly uncompressed and would be capable of yielding if the type members were brought to bear there against without further compression. Thus, in accordance with the present invention, there is provided a pressure member comprising a cut-out mat, die or pressure plate 153 carried by a frame 154 (Figs. 1, 2, 4 and 6), and the frame 154 is supported at either side of the machine by arms 155 which are each pivoted to the ends of the cross shaft 39 to which the movable bed 34 is pivoted. Thus, the pressure mat 153 and the moveable bed 34 are pivoted to and turn about the same pivot point and move in the same arc, the mat 153 being interposed between the movable bed 34 and the inclined opening edges of the book. The pressure mat 153 is normally held away from the book in position B during non-printing by springs 157 which are tensioned between the mat supporting arms 155 and the side frames 20 and 21, respectively. Similarly, the mat 153 is held in spaced relationship from the movable bed 34 by means of stop lugs 158 which are carried by the side frames 20 and 21 and engage the arms 155, thus preventing interference with the operation of the ink rollers 40 and 41.

As shown in detail in Fig. 16 of the drawings, the pressure mat 153, which is one form of pressure member found capable of performing its intended function, comprises a rigid backing plate 159 to which is secured a compressible sheet or section 160 of rubber or other resilient material, and on the outer face of the compressible sheet 160 there is secured a thin contact plate 161 of metal or other smooth surfaced material against which the opening edges may relatively move upon engagement therewith. The plate 159, the compressible sheet 160 and the contact plate 161 are each cut away to provide openings 162 which will be in alignment with the type members 57 when in printing position. Other forms of pressure mats may be utilized instead of that disclosed in the drawings. For instance, compression springs associated with metal strips operating between the type members may be utilized with satisfactory

results. The only requirement is that the opening edges be compressed to a substantially unyielding surface prior to and during printing. It is likewise apparent that the pressure member may be made incompressible and that the type members may be made movable so as to project therethrough after compression of the book opening edges.

When the bed 34 rocks to the left, as viewed in Figs. 1 and 2, toward closed printing position, it 10 engages the pressure mat 153 and causes it also to be rocked to the left, the mat openings 162 being in registry with the type members 57 upon initial engagement and this registry being maintained thereafter until completion of the printing operation due to the fact that the mat and type members follow the same arc in movement. Upon continued movement of the bed 34, the pressure mat 153 will first engage the inclined printing surface formed by the opening edges of 15 the book but the type members 57 will still be spaced away from the opening edges by the pressure mat 153. However, upon continued movement of the bed 34, the mat 153 is compressed under pressure and the type members 57 enter 20 through the openings 162 therein so as to bear against and print on the opening edges of the leaves and the marginal top surfaces of leaves adjacent the opening edges. As the mat 153 is compressed between the bed 34 and the book, a 25 substantial pressure is applied against the inclined printing surface of the opening edges of the book so that the portions of the leaves between the plane of their opening edges and the stationary platen board 62 are sufficiently compressed. This compression of the opening edges in a direction perpendicular to the surface of their inclined plane, together with the confining pressure provided by pressure bar 138, pressure chains 137, book clamp 99, and the locked position of rocker chute 65, presents a substantially rigid or solid printing surface which is relatively unyieldable when engaged by the type members 57. As a result, the printing impressions are 30 clear and sharp.

Upon completion of the printing operation, the bed 34 is rocked back to open Fig. 1 position, and the mat 153 under the urge of springs 157 follows the bed 34 away from the book until the arms 155 are engaged by the lugs 158. At the 35 same time, as explained above, the pressure bar 138 is released by disengagement of pressure cams 145 and 145c from rollers 151 and is removed from the book by the springs 144, the pressure applied by the chains 137 likewise being released. This release of pressure permits heavy springs 121 to move rocker chute 65 in a counter-clockwise direction out of engagement with locking arm 128 which is then retracted as previously described. Rocker chute 65 is then moved in a 40 clockwise direction by the tension of light springs 120, tension of heavy springs 121 being released by movement of bed 34. The book is thus restored to normal position with its opening edges in a plane substantially perpendicular to the plane of the leaves. Floating clamp bar 99 is 45 then raised out of contact with the book, at which time the book will slide downwardly from position B to position C, the stop pins 88 and 89 having previously been retracted upon movement of the bed 34 to printing position. The mechanism for effecting such retraction will now be described with reference to Figs. 6, 14 and 15.

The carrier 86 which supports the stop pins 88 and 89 also supports similar but slightly longer

pins 163 and 164, also projecting upwardly through the platen board 62 on either side of pins 88 and 89. The pins 163 and 164 are engaged by lugs 165 carried on either side of the chase 59 on the movable bed 34 as the bed approaches printing position, and they are depressed thereby so as to effect depression of the pin carrier 86 and the stop pins 88 and 89 below the top surface of the platen board 62. The carrier 86 is yieldably supported on the under side of the platen board 62 by springs 167 which encircle the pins 163 and 164, and which are adapted to be extended when the pins 163 and 164 are depressed by lugs 165 and to return the pins to their normal position projecting above the platen board 62. However, after the pins 88, 89, 163 and 164 have been depressed by the lugs 165 on the bed 34, the carrier 86 is engaged by a shoulder 168 on an angular locking arm 169, as shown in Fig. 15, in order that the pins 88 and 89 may be locked in retracted position until after the printing operation and after the book has slid on to position C. The locking arm 169 is pivoted to a bracket 170 mounted on the under side of the platen board 62 and is adapted to engage the carrier sleeve 76 and the roller 133 of roller carrier 134, previously described. When roller 133 engages the upper end of the locking arm 169, that arm is rocked in a clockwise direction so as to raise the shoulder 168 and release the carrier 86. The roller 133 does not engage the locking arm 169 until after the book has passed downwardly by gravity to position C. The pins 88 and 89 are thus released to their normal position where they will stop and support the next succeeding book sliding down from feeding position A.

Position C

As the book passes downwardly by gravity to position C from position B after being printed, it passes between transversely adjustable guide plates 171 and 172, which are also similar in general structure and operation to the guide plates of positions A and B, until it comes to rest against a counterbalanced stop 173 pivotally supported in a notch at the forward lower edge of the platen board 63 as at 176. This stop 173 is retained in book-arresting position by a notched latch bar 174 pivoted at its rearward end to a bracket 175 secured to the under surface of the platen board 63 at its upper end. The latch bar 174 is urged up into stop-latching position by a spring 177 and its upward movement is limited by a saddle stop 178 also depending from the under side of the platen board 63. Upon the completion of the operation in position C, the stop 173 is released by clockwise movement of the latch arm 174, the movement being effected by downward movement of a connecting arm 179 which is pivoted at its upper end to the latch bar 174 and at its lower end to the lower end of a vertically extending cam bar 180. Like the cam bars 79, 111 and 112, the cam bar 180 is also pivoted on the transverse shaft 81 and its upper end is adapted to be engaged and rocked to the right by a roller 181 mounted in a roller carrier 182 on the carrier sleeve 76 (Fig. 13). When the cam bar 180 is engaged and rocked to the right by the roller 181, the latch bar 174 is pulled downwardly, thus permitting the stop 173 to turn on its pivot 176 and to release the book to position D.

In position C one of the controlled off-setting steps of my improved process is performed and in accordance with which the book is permitted

to remain in normal unflexed position and pressure is applied against the surface of the top sheet adjacent the opening edges so as to compress the book at its opening edges against the platen board 63. By applying pressure perpendicularly to the plane of the leaves adjacent the opening edges, the ink impression which has been printed on the upper surfaces of the leaves adjacent their opening edges is definitely offset, while still wet, onto the under surfaces of the leaves immediately thereabove adjacent their opening edges. To this end, there is provided a pressure assembly comprising upstanding bracket arms 183 mounted on the inner sides of the side frames 20 and 21 and to the upper ends of which are pivoted rearwardly and upwardly extending offset pressure arms 184. Intermediate the ends of the pressure arms 184 is a cross bar 185 extending therebetween and having guide plates 187 depending on the ends thereof. The guide plates 187 are slotted to receive pins 188 projecting outwardly from the ends of a floating pressure bar 189 and this pressure bar is yieldably maintained in spaced relationship below the cross bar 185 by a plurality of compression springs 190 positioned over studs 191 on the upper surface of the pressure bar 189. The pins 188 are adapted to ride in the slots of the guide plates 187 as the floating pressure bar 189 moves toward or away from the cross bar 185 upon the increase or decrease in pressure.

As a book slides down into position C against the stop 173, the pressure assembly above described is held in the raised, inoperative position shown in Fig. 1 by means of compression springs 186, but as the movable bed 34 approaches printing position, the upper rearwardly extending ends of the pressure arms 184 are engaged and forced downwardly by rollers 192 carried on the ends of brackets 193 adjustably mounted on the inner respective sides of the legs of the movable bed 34. Downward movement of the pressure arms 184 causes the floating pressure bar 189 to engage the surface of the top sheet of the book adjacent the opening edges, and when the bed 34 is in full printing position, the springs 190 will be somewhat compressed and, as shown in Fig. 6 of the drawings, the leaves of the book adjacent the opening edges will likewise be compressed. This application of pressure will effect a definite controlled offsetting of the ink to the under surfaces of the leaves adjacent the opening edges, as above described.

After completion of the printing operation, the return of the bed 34 to open position will release the pressure assembly of position C to its raised position of Fig. 1, and thereafter, as above described, the latch bar 174 will release the stop 173 and permit the book to progress to position D for a further controlled offsetting operation.

Position D

As the book passes downwardly by gravity to position D after the application of the straight line, offsetting pressure, it passes between transversely adjustable guide plates 194 and 195 until it again comes to rest on the platen board 64 against a counterbalanced stop 197 pivotally adjacent its upper end to a bracket 198. The bracket 198 is rigidly mounted on the top of an upstanding transverse hanger 199 secured to the side frames 20 and 21 at their lower ends. The stop 197 is held in upright book-arresting position by the engagement of its lower end with a notched latch bar 200 extending at right angles to the

stop 197 underneath the platen board 64 and having its upper rearward end pivoted to a bracket 201 secured to the under surface of the platen board 64. The latch bar 200 is held up in stop-engaging position by a spring 202 and its counterclockwise movement is limited by a saddle stop 203, both the spring 202 and the stop 203 being secured to the under side of the platen board 64.

In order to release the stop 197 and to permit the book to pass out of the machine upon the completion of the last operation in position D, there is provided a connecting rod 204 having its forward end pivotally connected to the latch bar 200 intermediate its ends and its rearward end pivoted to the lower end of cam bar 205. The cam bar 205 is also pivoted on the cross shaft 81 and, as shown in Figs. 6 and 12, its upper end is adapted to be engaged and rocked forwardly by the roller 133 of roller carrier 134 upon rotation of the carrier. As the cam bar 205 is rocked forwardly, the connecting rod 204 is moved rearwardly, pulling the latch bar 200 out of latching contact with the stop 197 and permitting the stop to pivot as the book slides down under its own weight.

The vertical side plates of the hanger 199 are slotted and serve as vertical guides for pins 207 which project outwardly from the ends of a transverse floating clamp 208, the clamp 208 being confined for vertical movement therebetween and being spaced below and from the hanger 199 by a plurality of compression springs 209 positioned over studs 206 mounted on the floating clamp 208. A plurality of flat band springs 210 are attached to the under side of the floating clamp 208 and their forward ends, which extend forwardly beyond the chute board 64, are joined together by a transverse tie strip 211. Similarly, a plurality of flat band springs 212 are secured to the platen board 64 and also attached to their forward projecting ends are a similar transverse tie strip 213 and also an auxiliary cross bar 214 having rollers 215 mounted on its respective ends.

In order to permit the books to pass freely into and out of position D, a rearwardly extending guide plate 217 is attached to the under side of the floating clamp 208 and the floating clamp, as shown in Figs. 1 and 2, is held in raised position by arms 218 pivotally connected at their upper ends to the clamp bar pins 207 and at their lower ends to forward ends of cam bars 219. The rearward ends of the cam bars 219 are pivoted to pins 220 projecting from the side frames 20 and 21, and the lower edges of these cam bars are provided with a cam surface for engagement with rollers 221 mounted on the inner respective sides of the legs of the movable bed. In normal position shown in Fig. 1, the clamp bar 208 and the flat springs 210 are held in elevated position by the cam bars 219 and rollers 221, but after a book has reached the position against the stop 197 and as the bed 34 moves to printing position, the rollers 221 are moved rearwardly out of engagement with the cam bars 219, thereby permitting the floating clamp 208 to be pressed by the compression springs 209 downwardly against the upper surface of the book at a point somewhat removed from the opening edges thereof. In this clamped position the free opening edges of the book forwardly of the clamp 208 are supported in flat position under spring tension by the band springs 210 and 212, which serve to resist flexing movement of the book either up or down.

After the book has been clamped under tension in the manner just described, and as the bed 34 is continued to be rocked to printing position, cam bars 222 which are secured to the lower cross brace 34a between the vertical legs of the bed 34 and project forwardly therefrom under the chute board 64, are caused to engage and lift the rollers 215 against the tension of the flat springs 210 and 212. This bends the springs 210 and 212 upwardly and flexes the book in a direction opposite to that in which it was flexed for printing in position B. As the book is so flexed, the marginal portions of the upper surfaces of the leaves adjacent their opening edges are caused to wipe or slide against the under surfaces of the leaves immediately thereabove and adjacent their opening edges, thereby effecting another definite, controlled offsetting of the wet ink from one surface to the other.

When the bed 34 returns to normal position, the cam bars 222 are rocked downwardly, permitting the book to return to unflexed position. In returning to normal position, the surface portions of the leaves thereof again wipe or slide against each other but in the reverse direction. As the bed 34 moves toward its fully open position of Fig. 1, the floating clamp 208 and band springs 210 are raised and the stop 197 is unlatched, permitting the completely processed book to pass out of the machine.

It is to be understood that in position D the book may be flexed downwardly, as well as upwardly, with the opening edges thereof under compression in order to accomplish satisfactory and effective offsetting. This could be readily accomplished by a change in the shape of the cam bars 222 and by a change in the position of the rollers 221.

Summary of operation

When in operation, the machine above described is being continuously driven by a source of power and four books may be passing through the machine at one time for the progressive performance of the steps of my improved process thereon. When a book is in feeding position A on the inclined platen chute, a second book is in position B in flexed condition being printed on its opening and adjacent exposed edges, a third book is in position C in unflexed condition being compressed adjacent its opening edges to accomplish the first controlled offsetting step, and the fourth book is in position D being flexed under compression in a direction opposite to that in which it was flexed for printing to accomplish the second or weaving step of the offsetting procedure. When the operations in positions B, C and D are completed, the stops 197, 173 and 72 of positions D, C and A are released in sequence, allowing sufficient time to permit sliding of the respective books into their next positions, it being understood, however, that the stop pins 88 and 89 of position B were previously retracted upon movement of the bed 34 to printing position.

When the book slides downwardly into position B against the stop pins 88 and 89, it is clamped intermediate its back and opening edges in the rocker chute 65 by the floating clamp bar 99, after which, as the bed 34 moves to printing position, the rocker chute 65 is rocked rearwardly so as to flex the book over the rock shaft 95 and incline the opening edges of the book for printing. The book is further clamped around the rock shaft 95 and against the chute board 62 by

engagement of rollers 151 on the bed with the cam bars 145 and 145c which press downwardly the pressure bar 138 and draw chains 137 forwardly and downwardly against the flexed book. In so doing, the rocker chute 65 is locked in a fixed rearward position by locking arm 128 so that the opening edge of the lower page of the book is in the desired fixed and constant position, with the chains 137 conforming to the upper curved surface of the book. The combined mechanism serves to correctly position the opening edge of the top leaf of the book at the desired fixed point, regardless of reasonable variations of the thickness of the paper thereof. The resulting inclined printing surface formed by the opening edges of the book is then compressed upon engagement with and compression of the resilient mat 153 just before printing so as to present a substantially unyielding printing surface for engagement with the type members. Upon completion of printing and during return of the bed 34 to open position, the locking arm 128, pressure bar 138 and the chains 137 are released, the rocker chute 65 is rocked upwardly to normal position and the floating clamp bar 99 is raised, thereby permitting the printed book to slide down to position C.

In position C the pressure bar 189 is pressed against the book adjacent its opening edges in a direction perpendicular thereto by engagement of the rollers 192 with the ends of the pressure arms 184 so that the wet ink impressions on the upper surfaces of the leaves adjacent their opening edges are offset onto the under surfaces of the leaves immediately thereabove and adjacent their opening edges. Return of the bed 34 to open position releases the pressure bar 189 and the stop 173 is released by latch bar 174, thus permitting the book to slide downwardly to position D against stop 197.

In position D the book is flexed upwardly under pressure between the flat springs 210 and 212 in a direction opposite to that in which it was flexed for printing so as to cause a further controlled offsetting on the under surfaces of the sheets by a wiping or sliding action. This reverse flexing or weaving is accomplished by the cams 222 upon movement of the bed 34 to and from printing position. Upon return of the bed 34 to open position, the book is unflexed and then unclamped and upon release of the stop 197 slides downwardly out of the machine.

Upon inspection of a book whose edges have been printed by the improved machine above described and in accordance with the steps of the improved process, clear, sharp printing impressions may be observed on the opening edges of the individual leaves and also on the upper and lower surfaces of the leaves adjacent their opening edges, so that no matter whether the opening edges are in normal position or whether the book is flexed in either direction, the printing will be distinctly visible. It will also be found that the printing, regardless of reasonable variations in the thicknesses of the paper leaves of successive books of the same run, will be in proper and correct registry with the intended pages.

Although there has been shown in the drawings and described above an improved printing machine and process embodying my invention, it will be apparent that variations and modifications may be made without departing from the underlying principles of the invention. It is intended, therefore, by the following claims to include within the scope of the invention all variations and modifications by which the results of

the invention may be obtained through the use of substantially the same or equivalent means or steps.

I claim:

1. The process of printing upon the opening edges of the leaves of books so that the printed impressions will be in substantial registry with the intended leaves thereof regardless of reasonable variations of the thicknesses of the leaves of successive books, which comprises flexing a book intermediate its back and opening edges so as to arrange the opening edges in a plane inclined to the plane of the leaves and with the opening edge of the bottom leaf thereof being held to a predetermined position, then moving the upper leaf thereof under pressure applied over an area from its opening edge to a point rearwardly therefrom to compress said leaves under said area and then limiting the extent of said compressing movement to a predetermined fixed position to limit movement of the opening edge of the said upper leaf to a predetermined fixed position, whereby the opening edges of the upper and lower leaves of successive books may be successively placed in the same fixed positions for printing.

2. The process of printing upon the opening edges of the leaves of books so that the printed impressions will be in substantial registry with the intended leaves thereof regardless of reasonable variations of the thicknesses of the paper leaves of successive books, which comprises clamping the book under pressure intermediate its back and opening edges to maintain the back edges thereof in their normal relationship at all times, flexing the book intermediate its back and front opening edges about a radius so as to arrange the opening edges in a plane inclined to the plane of the leaves and with the opening edge of the bottom leaf thereof being held to a predetermined position, then moving the upper leaf thereof under pressure applied between its clamped area and its opening edge to compress said leaves and then limiting the extent of said compressing movement to a predetermined fixed position to limit movement of the opening edge of said upper leaf to a predetermined fixed position, whereby the opening edges of the upper and lower leaves of successive books may be successively placed in the same fixed positions for printing.

3. A machine for printing on the opening edges of books which comprises a supporting frame, a book supporting platen mounted on said frame, means for flexing a book intermediate its back and front opening edges so as to arrange the opening edges thereof in a plane inclined to the plane of the leaves, pressure means for compressing said book when in flexed condition in a direction perpendicular to the plane of the leaves thereof and engageable with the upper leaf thereof adjacent its opening edge, at the top of the inclined plane, a bed mounted on the frame, type members carried on said bed and adapted to engage and print on said inclined opening edges, means for effecting relative movement between said platen and said bed from open to closed printing position and return, and a pressure member adapted to engage and bear against said inclined opening edges prior to engagement of said type members therewith so as to compress said opening edges into a substantially rigid and unyielding printing surface.

4. A machine for printing on the opening edges of books which comprises a supporting frame, a book supporting platen mounted on said frame,

means for flexing a book intermediate its back and front opening edges so as to arrange the opening edges thereof in a plane inclined to the plane of the leaves, a bed mounted on said frame, projecting type members carried on said bed and adapted to engage and print on said inclined opening edges, means for effecting relative movement between said platen and said bed from open to closed printing position and return, and a pressure member having openings therein interposed between said platen and said bed and adapted to bear against inclined opening edges prior to engagement of the type members therewith whereby the opening edges are compressed into a substantially rigid and unyielding printing surface and said type members project through said pressure member openings to engage said opening edges.

5. A machine for printing on the opening edges of books which comprises a supporting frame, a stationary book supporting platen mounted on said frame, means supported on said frame for flexing a book intermediate its back and front opening edges so as to arrange the opening edges thereof in a plane inclined to the plane of the leaves, a movable bed mounted on said frame and adapted to be moved from open to closed printing position and return, projecting type members carried on said bed and adapted to engage and print on said inclined opening edges, and a compressible pressure member having openings therein between said platen and said movable bed and adapted to bear against said inclined opening edges prior to engagement of said type members therewith and to be compressed upon movement of said bed to printing position whereby the opening edges are compressed into a substantially rigid and unyielding printing surface and said type members project through said pressure member openings and engage said opening edges.

6. A machine for printing on the opening edges of books which comprises a supporting frame, a stationary book supporting platen mounted on said frame, means supported on said frame for flexing a book intermediate its back and front opening edges so as to arrange the opening edges thereof in a plane inclined to the plane of the leaves, a movable bed pivotally mounted on said frame and adapted to be rocked from open to closed printing position and return, projecting type members carried on said bed and adapted to engage and print on said inclined opening edges, and a compressible pressure member interposed in spaced relation from and between said platen and said bed and mounted for movement in the same arc as said bed, said pressure member being provided with openings and adapted to be engaged and forced against said inclined opening edges and to be compressed by said bed upon movement thereof to printing position whereby the opening book edges are compressed into a substantially rigid and unyielding printing surface and said type members are projected through said pressure member openings and engage said opening edges.

7. A machine for printing on the opening edges of books which comprises a supporting frame, a stationary book supporting platen mounted on said frame, means supported on said frame for flexing a book intermediate its back and front opening edges so as to arrange the opening edges thereof in a plane inclined to the plane of the leaves, a movable bed mounted on said frame and

adapted to be moved from opening to closed printing position and return, projecting type members carried on said bed and adapted to engage and print on said inclined opening edges, and a compressible pressure member having openings therein between said platen and said movable bed and adapted to bear against said inclined opening edges prior to engagement of said type members therewith and to be compressed upon movement of said bed to printing position whereby the opening edges are compressed into a substantially rigid and unyielding printing surface and said type members project through said pressure member openings and engage said opening edges, said pressure member comprising a back plate, a layer of resilient material secured to said back plate and a smooth flat sheet on the outer face of said resilient layer adapted to bear against said inclined opening edges during compression thereof.

8. A machine for printing upon the opening edges of books which comprises a supporting frame, a book supporting platen on said frame having a plurality of zones of operation, means operable in one zone of operation for flexing a book intermediate its back and front opening edges so as to arrange the opening edges thereof in a plane inclined to the plane of the leaves and to expose the marginal surface portions of the leaves adjacent the opening edges, a bed mounted on said frame, type members carried on said bed and adapted to engage and print on said inclined opening edges, means for effecting relative movement between said platen and said bed from open to closed printing position and return, means for restoring said book to normal position after printing with its opening edges in a plane substantially perpendicular to the plane of the leaves, means for passing said book to a second zone of operation, a pressure member operable in said second zone and adapted to compress said book adjacent its opening edges in a direction perpendicular to the plane of the leaves thereof while the ink is still wet, and actuating means for effecting compressing movement of said pressure member upon relative movement between said platen and said bed to printing position.

9. A machine for printing upon the opening edges of books which comprises a supporting frame, a stationary book supporting platen mounted in inclined position on said frame and having a plurality of zones of operations to which the books progressively pass by gravity, stop means for positioning a book in one zone of operation, means operable in said one zone of operation for flexing a book intermediate its back and front opening edges so as to arrange the opening edges thereof in a plane inclined to the plane of the leaves and to expose the marginal portions of the leaves adjacent the opening edges, a movable bed mounted on said frame and adapted to be moved from open to closed printing position and return, type members carried on said bed and adapted to engage and print on said inclined opening edges, means for restoring said book to normal position after printing with its opening edges in a plane substantially perpendicular to the plane of the leaves, means for releasing said stop means to permit said book to pass by gravity to said next zone of operation, stop means for positioning said book in said next zone of operation, a pressure member operable in said second zone and adapted to compress said book adjacent its opening edges in a direction perpendicular to the planes of the

leaves thereof, and actuating means mounted on said bed and adapted to engage and compress said pressure member upon movement of said bed to printing position.

10. A machine for printing upon the opening edges of books which comprises a supporting frame, book supporting platen on said frame, means for flexing a book intermediate its back and front opening edges so as to arrange the opening edges thereof in a plane inclined to the plane of the leaves and to expose the marginal surface portions of the leaves adjacent the opening edges, a bed mounted on said frame, type members carried on said bed and adapted to engage and print on said inclined opening edges, means for effecting relative movement between said platen and said bed from open to closed printing position and return, means for flexing said book in a direction opposite to that in which it was flexed for printing to offset the printed impressions from the upper surface edge portion of one sheet to the under surface edge portion of a sheet immediately thereabove, and means for maintaining the portions of the book leaves at and immediately adjacent the edges thereof under pressure during flexing in said opposite direction.

11. A machine for printing upon the opening edges of books which comprises a supporting frame, a stationary book supporting platen on said frame and having a plurality of zones of operation, means operable in one zone of operation for flexing a book intermediate its back and front opening edges so as to arrange the opening edges thereof in a plane inclined to the plane of the leaves and to expose the marginal surface portions of the leaves adjacent the opening edges, a movable bed mounted on said frame and adapted to be moved from open to closed printing position and return, type members carried by said bed and adapted to engage and print on said inclined opening edges, means for restoring said book to normal position after printing with its opening edges in a plane substantially perpendicular to the plane of the leaves, means for passing said book to another zone of operation, means for flexing said book in said other zone of operation to offset the printed impressions from the upper surface edge portions of one sheet to the undersurface edge portions of a sheet immediately thereabove, and means for maintaining the opening edge portions of the book leaves under pressure during offsetting flexing.

12. A machine for printing upon the opening edges of books which comprises a supporting frame, a stationary book supporting platen mounted in inclined position on said frame and having a plurality of zones of operations to which the books progressively pass by gravity, stop means for positioning a book in one zone of operation, means operable in said one zone of operation for flexing a book intermediate its back and front opening edges so as to arrange the opening edges thereof in a plane inclined to the plane of the leaves and to expose the marginal portions of the leaves adjacent the opening edges, a movable bed mounted on said frame and adapted to be moved from open to closed printing position and return, type members carried on said bed and adapted to engage and print on said inclined opening edges, means for restoring said book to normal position after printing with its opening edges in a plane substantially perpendicular to the plane of the leaves, means for

releasing said stop means to permit said book to pass by gravity to said next zone of operation, a second stop means for positioning said book in said next zone of operation, means operable upon movement of said bed to printing position for flexing said book in said other zone of operation, means for maintaining the opening edge portions of the book leaves under pressure during said flexing, and means for releasing said second stop means to permit said book to pass out of said other zone of operation.

13. A machine for printing upon the opening edges of books which comprises a supporting frame, a stationary book supporting platen on said frame, means for flexing a book intermediate its back and front opening edges so as to arrange the opening edges thereof in a plane inclined to the plane of the leaves and to expose the marginal surface portions of the leaves adjacent the opening edges, a movable bed mounted on said frame and adapted to be moved from open to closed printing position and return, type members carried by said bed and adapted to engage and print on said inclined opening edges, means for restoring said book to normal position after printing with its opening edges in a plane substantially perpendicular to the plane of the leaves, yieldable spring means adapted to support and compress said book at its upper and lower leaves and adjacent the opening edges thereof, and actuating means adapted upon movement of said bed to printing position to engage and flex said spring means whereby said book will be flexed to offset the printed impressions from the upper surface edge portions of one sheet to the under surface edge portions of a sheet immediately thereabove.

14. A machine for printing upon the opening edges of books which comprises a supporting frame, a book supporting platen having a plurality of zones of operation through which books successively pass, a movable bed mounted on said frame and adapted to be moved from open to closed printing position and return, means for moving said bed to and from printing position, means operable in one zone of operation for flexing a book intermediate its back and front opening edges so as to arrange the opening edges thereof in a plane inclined to the plane of the leaves and to expose the marginal surface portions of the leaves adjacent the opening edges, type members carried on said bed and adapted to engage and print on said inclined opening edges, means for restoring said book to normal position after printing, means for passing said book in normal condition to a second zone of operation, a pressure member operable in said second zone and adapted to compress said book adjacent its opening edges in a direction perpendicular to the planes of the leaves thereof while the ink is still wet, actuating means operable upon movement of said bed to and from printing position for effecting compressing movement of said pressure member and for effecting the release thereof, means for passing said book to a third zone of operation, means for flexing said book in said third zone upon movement of said bed to printing position and means for maintaining the opening edge portions of the book leaves under pressure during the flexing thereof.

15. In a machine for printing upon the opening edges of the leaves of books, a mechanism for maintaining proper registry of the printed impressions with the opening edges of the intended leaves regardless of reasonable variations of the

thicknesses of the leaves of successive books, comprising pressure means for clamping a book intermediate its back and front opening edges to maintain the back edges thereof in normal relationship during flexing of the book and printing, means for flexing the book intermediate its back and front opening edges so as to arrange the opening edges in a plane inclined to the plane of the leaves, means for limiting flexing movement of said book flexing means and engageable therewith at a fixed constant position so as to correctly position the bottom leaf of the book in a fixed predetermined position, a pressure member adapted to engage the upper leaf of said book adjacent its opening edge after said book has been flexed and to compress said leaves, and means for limiting the compression movement of said pressure member to a predetermined fixed position to limit movement of the opening edge of said upper leaf to a predetermined fixed position.

16. In a machine for printing upon the opening edges of the leaves of books, a mechanism for maintaining proper registry of the printed impressions with the opening edges of the intended leaves regardless of reasonable variations of the thicknesses of the leaves of successive books, comprising pressure means for clamping a book intermediate its back and front opening edges to maintain the back edges thereof in normal relationship during flexing of the book and printing, means for flexing the book intermediate its back and front opening edges so as to arrange the opening edges in a plane inclined to the plane of the leaves, means for supporting said book in said flexed position, means for limiting flexing movement of said book flexing means and engageable therewith at a fixed constant position so as to correctly position the bottom leaf of the book in a fixed predetermined position on said supporting surface, a pressure member adapted to engage the upper leaf of said book adjacent its opening edge after said book has been flexed and to compress said leaves against said book supporting means, flexible pressure means extending between said clamping means and said pressure member and adapted to engage and compress those portions of the book leaves between the clamping means and the pressure member upon compressing movement of said pressure member, and means for limiting the compressing movement of said pressure member to a predetermined fixed position to limit movement of the opening edge of said upper leaf to a predetermined fixed position.

17. In a machine for printing upon the opening edges of the leaves of books, a mechanism for maintaining proper registry of the printed impressions with the opening edges of the intended leaves regardless of reasonable variations of the thicknesses of the leaves of successive books, comprising a rockable member for flexing the book intermediate its back and front opening edges so as to arrange said opening edges in a plane inclined to the plane of the leaves for printing, pressure means on said rockable member for clamping a book intermediate its back and front opening edges to maintain the back edges thereof in normal relationship, means for limiting flexing movement of said rockable member and engageable therewith at a fixed constant position so as to correctly position the bottom leaf of the book in a fixed predetermined position, means for supporting the front opening portions of the book

leaves while in flexed position, a pressure member adapted to engage the upper leaf of said book adjacent its opening edge after said book has been flexed and to compress said leaves against said supporting means, flexible pressure means extending between said clamping means and said pressure member and adapted to engage and compress those portions of the book leaves between the clamping means and the pressure member upon compressing movement of said pressure member, and means for limiting the compressing movement of said pressure member to a predetermined fixed position to limit movement of the opening edge of said upper leaf to a predetermined fixed position.

18. A machine for printing on the opening edges of books which comprises a supporting frame, a book supporting platen mounted on said frame, pressure means for clamping a book intermediate its front opening and back edges to maintain the back edges thereof in their normal relationship during flexing and printing, means for flexing a book intermediate its front opening edges and said pressure means so as to arrange the opening edges thereof in a plane inclined to the plane of the leaves, pressure means adapted to compress in their flexed positions those portions of the book leaves extending from said first pressure means to the opening edge of the top leaf thereof, a bed supported on said frame, type members carried on said bed and adapted to engage and print on said inclined opening edges, means for effecting relative movement between said platens and said bed from open to closed printing position and return, and pressure means adapted to engage and bear against said inclined opening edges prior to engagement of said type members therewith so as to compress said opening edges into a substantially rigid and unyielding printing surface.

19. A machine for printing on the opening edges of books which comprises a supporting frame, a book supporting platen mounted on said frame, pressure means for clamping a book intermediate its front opening and back edges to maintain the back edges thereof in their normal relationship during flexing and printing, means for flexing a book intermediate its front opening edges and said pressure means so as to arrange the opening edges thereof in a plane inclined to the plane of the leaves, pressure means adapted to compress in their flexed positions those portions of the book leaves extending from said first pressure means to the opening edge of the top leaf thereof, said second pressure means comprising a pressure member adapted to engage said book at the opening edge of the top leaf thereof and flexible pressure members extending from said first pressure means to said second pressure means and adapted to engage the top leaf of said book in its flexed condition between said first and second pressure means, a bed supported on said frame, type members carried on said bed and adapted to engage and print on said inclined opening edges, means for effecting relative movement between said platen and said bed from open to closed printing position and return, and pressure means adapted to engage and bear against said inclined opening edges prior to engagement of said type members therewith so as to compress said opening edges into a substantially rigid and unyielding printing surface.

20. A machine for printing on the opening edges of books which comprises a supporting frame, a book supporting platen mounted on said

frame, pressure means for clamping a book intermediate its front opening and back edges to maintain the back edges thereof in their normal relationship during flexing and printing, means for flexing a book intermediate its front opening edges and said pressure means so as to arrange the opening edges thereof in a plane inclined to the plane of the leaves, pressure means adapted to compress in their flexed positions those portions of the book leaves extending from said first pressure means to the opening edge of the top leaf thereof, a bed supported on said frame, type members carried on said bed and adapted to engage and print on said inclined opening edges, means for effecting relative movement between said platen and said bed from open to closed printing position and return, and pressure means having openings therein and adapted to bear against said inclined opening edges prior to engagement of said type members therewith, whereby the opening edges are compressed into a substantially rigid and unyielding printing surface and said type members project through said pressure means openings and engage said unyielding printing surface.

21. In a machine for printing upon the opening edges of the leaves of books, a mechanism for maintaining proper registry of the printed impressions with the opening edges of the intended leaves regardless of reasonable variations of the thicknesses of the leaves of successive books which comprises means for flexing the book intermediate its back and front opening edges so as to arrange the opening edges in a plane inclined to the plane of the leaves, means for limiting flexing movement of said book flexing means and engageable therewith at a fixed constant position so as to correctly position the bottom leaf of the book in a fixed predetermined position, a pressure member adapted to engage the upper leaf of said book adjacent its opening edge after said book has been flexed and to compress said leaves, and restricting means operable on said pressure member for limiting the extent of compression movement of said pressure member and for stopping it at a predetermined fixed

position to limit the extent of movement of the opening edge of said upper leaf to said predetermined fixed position.

22. In a machine for printing upon the opening edges of the leaves of books, a mechanism for maintaining proper registry of the printed impressions with the opening edges of the intended leaves regardless of reasonable variations of the thickness of the leaves of successive books which comprises means for flexing the book intermediate its back and front opening edges so as to arrange the opening edges in a plane inclined to the plane of the leaves, means for limiting flexing movement of said book at a fixed constant position so as to correctly position the bottom leaf of the book in a fixed predetermined position, flexible pressure means extending rearwardly from the opening edges of the upper leaf of the book and adapted to engage and compress the flexed portions of the book leaves, and means for limiting the extent of compression movement of said flexible pressure means to a predetermined fixed position to limit movement of the opening edge of said upper leaf to a predetermined fixed position.
